UNITED STATES PATENT OFFICE

2,518,282

LAMP HOUSING

Don Canada, Cincinnati, Ohio, assignor, by mesne assignments, to The Hobart Manufacturing Company, Troy, Ohio, a corporation of Ohio

Application December 10, 1946, Serial No. 715,270

2 Claims. (Cl. 240—47)

1

This invention relates to a lamp housing for an electric light source of the high wattage calibre. Usually, in lamps of this nature which are used primarily in motion picture projectors and slide projectors, the lamp is of a wattage which generates considerable heat and unless suitable means are provided, the housing and parts near the lamp become excessively hot and create unreasonable trouble.

In this type of construction it is usual to incorporate a fan for blowing a stream of air about the lamp bulb, but in the case of high wattage lamps and without shields it is impractical to provide sufficient air stream to keep the housing cool.

My improved structure provides means for absorbing and reflecting the heat whereby the air stream will carry away all the heat and the lamp housing remains practically cool.

The object of my invention is to provide a pair of sleeves about the lamp and between the lamp and the outer housing and the surfaces are so coated that the heat will be absorbed and reflected into the air stream.

A further object is to provide means whereby the air can be exhausted from the lamp housing without permitting light to pass into the room where the projector is used.

My invention will be further readily understood from the following description and claims and from the drawings, in which latter;

Fig. 1 is a vertical section of the device, taken in the plane of the line 1—1 of Fig. 2.

Fig. 2 is a plan view of the lamp housing with certain parts removed and the case broken away to more clearly show the mechanism.

Fig. 3 is a top view of the lamp housing.

Fig. 4 is a vertical section of the baffles, taken in the plane of the line 4—4 of Fig. 3.

Fig. 5 is a horizontal section, taken in the plane of the line 5—5 of Fig. 1.

My improved lamp housing is arranged to be attached to a vertical panel 11 forming part of the projection device. Attached rigidly to this panel is a curved corrugated portion 12 forming the remainder of the lamp housing proper.

Ribs 13 extend from the curved portion of the panels 11 and corrugated portion 12 and form a circular base for supporting the lamp and the shields hereinafter described. The circular portion of the ribs 13 supports a lamp 15 having a cap 16 attached thereto to deflect the air around the lamp. Also the electrical connections to the lamp extend through this cap 16.

Within the lamp housing 12 and spaced from the lamp 15 is a tubular member 17 having a

flared base 18 which rests on the ribs 13. The inner face of this tubular member is coated with a dull black paint to absorb the radiated heat from the lamp 15, thus preventing the heat from rebounding into the lamp 15 which would intensify its own heat.

The outer surface 19 of this tubular member is coated with a mirror-like finish and is provided with pins 20 to space the sleeve 17 from a second sleeve 21, which has flared upper and lower ends 22 and 23. This second sleeve also rests on the ribs 13, and has bent out portions 24 at its upper circumference to rest against the housing 12. The inner surface of this second sleeve is of a mirror-like finish and the outer surface is of a dull black finish, while the inner surface of the housing 12 is provided with a mirror-like finish.

A grill 25 is arranged in the aperture 26 in the top of the housing and has depending vanes 27 which are angularly positioned for a portion of the length and then drop straight down. These vanes permit the air from the fan to pass through the upper portion of the housing and deflect the air away from the operator, while the light beams which would normally project from this opening and expand into the room are broken and very little light passes from the top of the housing.

The sleeve 17 and the sleeve 21 and the outer housing 12 are provided respectively with apertures 28, 29 and 30 to permit the light from the lamp 15 to be projected to the condenser lens system 31 for projecting the light to the mechanism of the projector.

A very efficient lamp housing is thus created, wherein the air stream passes around the lamp between the sleeves and the housing, and further, by using the light absorbing faces and reflecting surfaces of the sleeves and housing, considerable volume of the heat generated by the lamp is retained in the area of the sleeves and carried off by the air stream preventing the lamp from overheating or the outer housing from becoming too hot to touch.

Having thus fully described my invention, what I claim as new and desire to secure by Letters Patent, is:

1. A lamp housing for a projection device comprising a corrugated housing attached to said projection device, a lamp holder of a web-like structure extending from said projection device into said housing, a lamp in said holder, a sleeve spaced from said lamp and supported on said web-like structure and provided with a heat absorbing inner finish and a heat reflecting outer

surface, a second sleeve spaced from and about said first named sleeve by means of pins extending from one of said sleeves and supported on said web-like structure and provided with an inner heat reflecting surface and an outer heat absorbing finish, said corrugated housing having a heat reflecting inner surface, and projections on said second named sleeve for positioning said second named sleeve in spaced relation within said housing.

2. A lamp housing for a projection device comprising a corrugated housing attached to said projection device, a lamp holder of a web-like structure extending from said projection device into said housing, a lamp in said holder, a sleeve spaced from said lamp supported on said web-like structure and provided with a heat absorbing inner finish and a heat reflecting outer surface, a second sleeve spaced from and about said first named sleeve by means of pins extending from one of said sleeves and supported on said web-like structure and provided with an inner heat reflecting surface and an outer heat absorbing

5 finish, said corrugated housing having a heat reflecting inner surface, and projections on said second named sleeve for positioning said second named sleeve in spaced relation within said housing, and deflectors in the top of said housing for deflecting the heat and light rays.
